(57) **CLAIM**

The ornamental design for an antenna assembly, as shown and described.

DESCRIPTION

FIG. 1 is a top plan view of an antenna.

FIG. 2 is a side elevation view of the antenna of FIG. 1.

FIG. 3 is a bottom plan view of the antenna of FIG. 1.

FIG. 4 is an exploded perspective view of the antenna of FIG. 1.

FIG. 5 is an isolated isometric view of a first antenna element of the design shown in FIGS. 1-4.

FIG. 6 is an isolated front elevation view thereof.

FIG. 7 is an isolated side elevation view thereof.

FIG. 8 is an isolated bottom view thereof.

FIG. 9 is an isolated isometric view of a second antenna element of the design shown in FIGS. 1-4.

FIG. 10 is an isolated front elevation view thereof.

FIG. 11 is an isolated side elevation view thereof.

FIG. 12 is an isolated bottom plan view thereof.

FIG. 13 is an isolated isometric view of a third antenna element of the design shown in FIGS. 1-4.

FIG. 14 is an isolated front elevation view thereof.

FIG. 15 is an isolated side elevation view thereof.

FIG. 16 is an isolated side elevation view thereof; and,

FIG. 17 is an isolated top plan view of the antenna connector element of the design.

The broken lines illustrate environment that forms no part of the claimed design.
